Inventor:
Almon E. Norris,
by Emery Booth, James Harvey, Atlys.

UNITED STATES PATENT OFFICE.

ALMON E. NORRIS, OF BROOKLINE, MASSACHUSETTS.

BUFFER DEVICE.

Application filed May 5, 1924. Serial No. 710,961.

To all whom it may concern:

Be it known that I, ALMON E. NORRIS, a citizen of the United States, and a resident of Brookline, in the county of Norfolk and State of Massachusetts, have invented an Improvement in Buffer Devices, of which the following description, in connection with the accompanying drawings, is a specification, like characters on the drawings representing like parts.

This invention relates to buffer devices for moving vehicles, the illustrative form of the invention being embodied in a buffer device intended for bringing to rest a movable trolley carriage on an elevated trackway, although it may have various other applications.

The invention will be best understood by reference to the following description when taken in connection with the accompanying illustration of one specific embodiment thereof, while its scope will be more particularly pointed out in the appended claims.

25 In the drawings,—

Fig. 1 is a plan view showing a buffer device equipped with one form of the invention; and

Fig. 2 is a side elevation of the buffer device shown in Fig. 1.

Referring to the drawings and to the illustrated embodiment of the invention, I have there shown a buffer device of the general type shown in my prior Patent No. 1,323,608, dated December 2, 1919. This consists of a rectangular frame having sides 3 formed of angle irons, the under sides of which are each provided with a buffer plate or shoe 5 located above the respective rails 40 of the trackway 7 on which the trolley carriage or other vehicle is adapted to travel. The sides 3 of the frame are connected by cross pieces 9, the latter being united by the diagonal braces 11. They are suspended at their rear ends by links 13 pivoted on supports 15 secured to the cross girder 17, the latter comprising a part of the stationary buffer framework and supported by the upright girders 19. The two forward corners of the frame are suspended by the links 21 pivoted at 23 to overhead supports 25 secured to the upright girders 27. The bolts 29 which connect the sides 3 to the links 21 each work in a slot 31 in its link so that the frame is capable of be-

ing lifted slightly at its front end relatively to the links, as represented in the full line position in Fig. 2. The bolts 29 also serve pivotally to secure to the side members 3 a spring supporting bracket 33 between which and a corresponding overhead bracket 35 pivoted with the links at 23 there is provided a series of springs 37 of suitable strength to secure the desired friction of the buffer shoe against the trolley wheels.

When the trolley wheel reaches the position, represented at *x* in Fig. 2, it contacts with the under face of the shoe and the momentum causes the forward end of the buffer frame to lift slightly, compressing the springs 37, the bolts 29 lifting in the slots 31. As the trolley wheel advances beneath the buffer frame, it meets with an increasing friction, the springs exerting an increasing leverage as the wheel moves toward the position *y*. This increased braking effect brings the trolley to rest before it reaches the position *y*, there being, however, provided cushion blocks 39 to act as safety stops.

When the trolley moves into the buffer the frame is brought to rest against the stops 41. Owing to its suspension on the links, however, the frame is free to move in the opposite direction, such opposite movement, due to the link suspension, being accompanied by a lifting movement and a withdrawal of the frictional pressure of the shoe from the trolley wheel. On the first movement of the trolley, therefore, the frame is moved toward the dotted line position (indicated at Fig. 2) releasing the wheels.

A buffer of this description depends for its effectiveness on its frame being normally in its rearward position against the stops 41. If, when the trolley reaches the buffer, the latter is in a position approximating the dotted line position shown, it becomes less effective and may be entirely ineffective in checking the momentum of the car. Due to the rusting of the connections or improper installation of the frame, or other causes, it may happen that the buffer, when thrown outward by the previous withdrawal of the trolley carriage, tends to remain in that position (such as the dotted line position shown) and thereby become ineffective to serve its intended purpose.

To eliminate the danger of the failure of this automatic buffer device and to maintain the buffer normally in its rearward position, while permitting it at all times to be swung outwardly and upwardly under the pull of the trolley carriage, I have provided an automatic restoring device. For this purpose two springs 43 are herein shown anchored each at one end to the eye-bolt 45 5 fastened to the cross girder 17 and at the opposite end to fastenings 47 on the central cross member 9. These springs serve normally at all times to draw the buffer frame back against the stops 41 so that the trolley carriage is assured of having exerted against it full friction of the buffer shoe 5 and buffer springs 37, but they act with yielding force, such that the reversal of the trolley carriage movement will suffice to swing the frame outward, distending the springs and permitting the release of the carriage.

While I have herein shown for the purpose of illustration one specific embodiment of the invention, it is to be understood that 25 extensive deviations may be made therefrom without departing from the spirit thereof.

Claims.

1. The combination with a trackway, of a 30 wheeled vehicle and a buffer, the latter comprising a frame adapted to engage the wheels and check the movement of the vehicle, links suspending said frame and permitting inward and outward movement thereof, means for forcing the receiving end 35 of the frame toward the wheels, the suspension of the frame being such as to relieve the pressure on its outward movement under the reverse movement of the trolley, and

yieldable means normally drawing the frame toward its inward position. 40

2. The combination with a trackway, of a buffer frame, suspension links for the frame, the latter being movable vertically at the receiving end thereof, resilient means normally pressing said forward end toward a wheel engaging position, and a spring normally moving the frame inwardly. 45

3. The combination with a trackway, of a buffer frame, means supporting the frame to permit inward and outward movement, 50 means yieldably pressing the truck receiving end of the frame toward the trackway, said frame being yieldable on outward movement of the truck, and means yieldably holding the frame toward its inward position. 55

4. The combination with a trackway, of a buffer member suspended above the trackway, the outward end of the frame having a 60 yieldable suspension and said frame when moved outwardly having imparted thereto a lifting movement, and means for yieldably moving the frame to its inward position.

5. The combination with a trackway, of a buffer comprising a frame, the outward end 65 of which is resiliently supported to yield upwardly, and the frame as a whole being mounted to move outwardly and upwardly, a stop to position the frame normally in its inward movement, and means yieldably moving said frame inwardly toward its stop position. 70

In testimony whereof, I have signed my name to this specification.

ALMON E. NORRIS.
